ABSTRACT

A magnetic key suitable for use with electronic equipment comprises a magnetically controllable semiconductor device mounted between two soft iron pole pieces, and a permanent magnet movable relative to the device. The magnet is carried by a slide movable between two positions and biased by a spring towards one of the positions. In one position only a substantial part of the magnetic flux of the magnet passes through the device, so the condition of the device can be controlled by movement of the slide.

MAGNETIC KEYS

BACKGROUND OF THE INVENTION

Numerous different embodiments of magnetic keys, particularly, but not exclusively, designed to be fitted in electronic equipment, are already known. The invention relates specifically to such keys in which a change in the position of a magnet relative to a magnetically controllable semiconductor device produces a change in the electrical resistance of the semiconductor device. So-called field plates have already been used for this purpose; with these, the electrical resistance is known to depend on the strength of the magnetic field permeating them.

SUMMARY OF THE INVENTION

One object of the present invention is to provide a new or improved magnetic key.

Another object of the present invention is to provide a particularly advantageous form of magnetic key, which is simple and therefore cheap to produce, and with which good durability and great security of operation is also obtained.

According to the present invention there is provided a magnetic key comprising a casing, a slide mounted in the casing for linear movement between two positions, spring means urging the slide towards one of said positions, a permanent magnet carried by the slide and having a North pole and a South pole aligned in the direction of said movement of the slide, two pole pieces mounted within the casing, a magnetically controllable semiconductor device mounted between the pole pieces, the arrangement being such that in one of said positions of the slide said two poles of the magnet are adjacent to the two pole pieces respectively whereby a substantial part of the magnetic flux of the magnet passes through said device, and in the other of said positions of the slide said two poles of the magnet are both adjacent to one of the two pole pieces.

The result is that in one of said positions of the slide the magnetically controllable semiconductor device is permeated by a many times stronger magnetic field than in the other of said positions. The electrical resistance of the device is consequently dependent on the position of the slide, and this physical effect can be used in known manner to generate electric switching pulses.

The casing is preferably of plastics material and has on the inside two grooves disposed parallel to said direction, and the slide is provided with two rib-like projections slidable in respective grooves.

It is advantage for the two pole pieces to be plate-shaped and made of magnetically soft iron.

In a preferred embodiment of the invention said device is plate-shaped, the end faces of the two pole pieces which face towards one another are parallel with one another and substantially perpendicular to said direction, and the two large surfaces of said device extend perpendicular to said direction.

In order to make maximum use of the flux emanating from the permanent magnet, it has been found desirable to taper the cross section of one pole piece in the direction of said device preferably to less than half.

Naturally, it will be appreciated that many variations may be effected without departing from the spirit and scope of the present inventive concept.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing in which corresponding parts have been given the same reference numerals.

BRIEF DESCRIPTION OF THE DRAWING

FIG. 1 is a longitudinal section through the key;

FIG. 2 is a section on the line A—B of FIG. 1; and

FIG. 3 is a constructional detail on a larger scale.

DESCRIPTION OF THE PREFERRED EMBODIMENTS

Referring to FIG. 1, the magnetic key comprises a plastics case 1, in which a plastics slide 2, arranged at right angles, is movably mounted and linearly displaceable against the force of a spring 3 between two limit positions. As can be seen clearly from FIG. 2, the slide 2 is provided on two opposite sides with projecting ribs 4 and 4', respectively; the ribs 4 and 4' being guided in corresponding grooves 5 and 5' respectively in the case 1. The slide 2 carries a generally U-shaped permanent magnet 6 with its North and South poles aligned on behind the other in the direction of movement of the slide 2. Within the case 1, in the region of the magnetic field of the permanent magnet 6, is mounted a magnetically controllable 10 semiconductor device 7, which, during operation, has a current flowing through it. The electrical resistance of the device 7 can be varied by varying the strength of the magnetic field in which it is disposed. Such devices are commercially obtainable, for example, under the name of field plates. The device 7 is secured between the soft iron plates 9 and 9'.

By providing appropriate stops or by suitably shaping the case 1 and/or the slide 2, the displacement path of the slide 2 is limited, so that, in one limit position, that is the inoperative position which is shown in FIG. 1, the slide 2 is urged upwardly (as viewed in FIG. 1) by the force of the spring 3. By pressing a knob 10 fixed on the slide 2, the slide 2 can be moved into the other limit position. The device 7 is so mounted relative to the magnet 6 that in the first-mentioned position of the slide 2 a far larger proportion of the magnetic flux between the poles of the magnet 6 flows through the device 7 than in the other position of the slide 2.

In FIG. 1 position substantially all the magnetic flux of the magnet 6 passes through the device 7, the plates 9 and 9' acting as pole pieces and concentrating the flux through the device 7. When the knob 10 is depressed, the magnet 6 will be disposed such that the plate 9' extends across both poles of the magnet 6, so that substantially all the magnetic flux passes through the plate 9', and so does not pass through the device 7. When the knob 10 is depressed, the ohmic resistance of the device 7 is thus changed, and this can be caused to generate a switching pulse. For this purpose, the device 7 is coupled via connecting leads (not shown) to the control circuit of a logic element mounted on a support 11.

It is preferable for the device 7 to be in series with an ohmic resistor in a voltage divider circuit, and for the connecting point to be coupled to the control electrode of a transistor. The parameters are selected such that a change in the ohmic resistance of the device 7 will so change the potential of the control electrode of the transistor that the transistor passes from the blocked to the conductive state or vice versa. A material which has proved particularly successful for the magnet 6 is ALNICO 450.

FIG. 3 is a side view on a larger scale of the plates 9 and 9'. Between the two plates 9 and 9' is the device 7, the top and bottom end faces of which (as viewed in FIG. 3) have, in one embodiment, the dimensions 1.7 × 3.7 mm. The active surface on the top of the device 7 has the dimensions 0.7 × 1.7 mm. In order that the magnetic flux of the magnet 6 can be utilized as effectively as possible, that is supplied via the plates 9 and 9' to the active surface of the device 7, the end of the plate 9 abutting the device 7 is tapered to one third of the area of the non-tapered cross section of the plates 9. In the example illustrated, the thicknesses of the plates 9 and 9' are 0.8 and 1.5 mm respectively, while both plates 9 and 9' have a width of 45 mm (in the non-tapered portion). An angle of 45° has been found useful for the wedge-like tapering of the plate 9.

In the embodiment illustrated, displacement of the knob 10 and of the magnet 6 coupled thereto causes the ohmic resistance of the device 7 to be changed in the ratio 1:5. This change in resistance, obtained with simple means, is not merely adequate for virtually all fields of application, but also ensures security of operation.

Many possible modifications will become apparent from the foregoing without departing from the spirit of the present in-

vention. However, the foregoing disclosure is presented in an illustrative sense rather than a limiting sense and the appended claims are relied upon to define the scope of the present invention.

What is claimed as new and desired to be protected by Letters Patent is set forth in the appended claims.

What is claimed is:

1. A magnetic key comprising a casing, a slide mounted in the casing for linear movement between two positions, spring means urging the slide towards one of said positions, a permanent magnet carried by the slide and having a North pole and a South pole aligned in the direction of said movement of the slide, two pole pieces mounted within the casing, a magnetically controllable semiconductor device mounted between the pole pieces, the arrangement being such that in one of said positions of the slide said two poles of the magnet are adjacent to the two pole pieces respectively whereby a substantial part of the magnetic flux of the magnet passes through said device, and in the other of said positions of the slide said two poles of the magnet are both adjacent to one of the two pole pieces.

2. A key according to claim 1 wherein the casing is made of plastics material.

3. A key according to claim 2 wherein the casing has on the inside two grooves disposed parallel to said direction, and the slide is provided with two rib-like projections slideable in

respective grooves.

4. A key according to claim 3 wherein the slide is made of plastics material.

5. A key according to claim 1 wherein the magnet is generally U-shaped.

6. A key according to claim 1 wherein the two pole pieces are plate-shaped and made of magnetically soft iron.

7. A key according to claim 6 wherein one pole piece, as measured in said direction, is substantially longer than the other pole piece, and said one pole piece is arranged in the casing such that in said other of said positions of the slide said two poles of the magnet are both adjacent to said one pole piece.

8. A key according to claim 7 wherein the end faces of the two pole pieces, which face towards one another, are parallel with one another and substantially perpendicular to said direction, said device in plate-shaped, and the two large surfaces of said device extend perpendicular to said direction.

9. A key according to claim 8 wherein the cross section of one pole piece is tapered in the direction of said device.

10. A key according to claim 9 wherein the end face of the tapered pole piece has at most one third of the cross-sectional area of the non-tapered part of said pole piece.
